(57) **CLAIM**

The ornamental design for a computer, as shown and described.

DESCRIPTION

FIG. 1 is a front, top, left-side perspective view of a computer in accordance with our new design;

FIG. 2 is a front elevational view of the computer shown in FIG. 1;

FIG. 3 is a rear elevational view of the computer shown in FIG. 1;

FIG. 4 is a right-side elevational view of the computer shown in FIG. 1;

FIG. 5 is a left-side elevational view of the computer shown in FIG. 1;

FIG. 6 is a top plan view of the computer shown in FIG. 1;

FIG. 7 is a bottom plan view of the computer shown in FIG. 1; and,

FIG. 8 is a rear, bottom, right-side perspective view of the computer shown in FIG. 1.

The broken lines within the figures represents portions of the computer that form no part of the claimed design. The stippling represents a contrast in appearance between the stippled areas and the non-stippled areas, and no particular color, material, or finish is claimed.
